UNITED STATES PATENT OFFICE.

ISIDOR LYMAN, OF CLEVELAND, OHIO.

ATTACHMENT FOR DENTAL ENGINES.

SPECIFICATION forming part of Letters Patent No. 767,705, dated August 16, 1904.

Application filed July 1, 1903. Serial No. 163,887. (No model.)

To all whom it may concern:

Be it known that I, ISIDOR LYMAN, a citizen of the United States of America, residing at Cleveland, in the county of Cuyahoga and State of Ohio, have invented certain new and useful Improvements in Attachments for Dental Engines; and I hereby declare the following to be a full, clear, and exact description of the invention, such as will enable others skilled in the art to which it pertains to make and use the same.

This invention relates to improvements in dental engines.

The object of this invention is to provide a new and useful improvement in a dental engine by means of which either a constant or intermittent stream of water or blast of air can be caused to play upon the tooth while it is being operated upon by the dental instrument and by means of which an antiseptic or anesthetic can be sprayed upon the tooth.

My invention particularly consists in providing means by which the regular pedal of the machine can be caused to actuate the attachment to a greater or less extent, according to the requirements of the operator, and by means of which the attachment can be instantly thrown out of operation.

My invention also consists in the features of construction and combination of parts illustrated in the drawings, hereinafter described in the specification, and pointed out in the claims.

In the accompanying drawings, Figure 1 is a side elevation of a dental engine provided with my attachment. Fig. 2 is a section on line 2 2, Fig. 1, somewhat enlarged. Fig. 3 is a section on line 3 3, Fig. 2. Fig. 4 is a section on line 4 4, Fig. 3. Fig. 5 is an enlarged sectional view of the liquid-receptacle.

Again referring to the drawings, 1 represents the base, and 2 the upright, of the stand which supports a dental engine of the usual construction, comprising a pedal 3 and a crank-wheel 4, which is operatively connected to the pedal 3 by a pitman 5 and to the driving-wheel 6 by a belt 7. A flexible shaft 8 is operatively connected to the driving-wheel 6 in the usual manner. On the end of the flexible shaft 8 is secured a handpiece 9.

On the upright 2 is secured a small bracket 12 by means of a screw 13. On top of the bracket 12 is mounted a small bellows of the usual construction, comprising a body portion 14, which is provided with a spout 15. The spring 16 of the bellows is preferably arranged between the handle portion 17 and 18 of the bellows, so that it can be renewed without disturbing the body portion of the bellows. The bellows is secured to the bracket by means of a bolt 19.

On the upright 2 above the bellows is arranged a bracket 20, which supports a receptacle 21, suitable for holding a liquid which may be either water for cleansing the tooth which is being operated upon or a medicinal liquid for treating the teeth or gums.

In the top of the receptacle 21 is arranged a stopper 22, in which are formed two openings in which are arranged tubes 23 and 24, respectively, which fit snugly in the said openings, but are arranged to slide in the said openings so that they can be alternately raised or lowered, as desired. The tube 23 is connected directly with the bellows by means of a flexible tube 25. To the tube 24 is secured a flexible tube 26, in the end of which is secured a nozzle 27. This nozzle is provided with clamps 28, by means of which it is secured to the handpiece of the dental engine. Between the liquid-receptacle and the bellows is arranged a bracket 29, which forms a support for an alcohol-lamp 30 for heating the receptacle 21.

On the pedal 3 is arranged my device for controlling the operation of the bellows. This device comprises a small block 34, which is provided with flanges 35, which engage the under side of the pedal. Screws 36 are provided for securing the flanges to the pedal. In the block 34 is formed a groove or slide-way 37. In the slideway 37 are formed a series of holes 38, in which are removably secured teeth or projections 39. In the slideway 37 is mounted a small carriage 40, which carries a pawl 41, which when in its normal position will engage with the teeth or projections 39. In the carriage 40 is mounted a stud 42, which rests on the pawl and when pressed down will lift the pawl out of engagement with the projection 39 on the bottom of 100

the slideway. In the carriage 40 is secured a pin 43, and in the block 34 is secured a pin 44. A cord 45 is secured to the pin 43 and is carried under the pin 44 and then up to the arm 5 17 of the bellows.

The operation of this device is as follows: If the operator desires to have a constant stream of water, the tube 23, which is directly connected with the bellows, is arranged 10 so that its lower end will be above the liquid in the receptacle 21, and the tube 24, which is connected with the nozzle on the handpiece, is arranged so that its lower end will be immersed in the liquid, or if the operator desires to produce a spray he will arrange the 15 tubes in exactly the reverse position. When the operator desires to start the operation of the bellows, he shifts the carriage 40 in the slideway 37 until it engages with the tooth 39 20 at the left end thereof, and then when the pedal is depressed it will cause a compression of the bellows. When the operator desires to stop the operation of the bellows, he taps the stud 42 with his foot, thus disengaging the 25 pawl, and the carriage will move to the opposite end of the slideway, thus allowing the cord 45 to become slack, and thereafter depressing the pedal will not operate the bellows. If the operator does not wish the bellows to be entirely compressed with each 30 stroke of the pedal, he can move the tooth 39 at the left end toward the tooth at the right end, thus allowing a certain amount of slack in the cord 45 all the time.

35 What I claim is—

1. The combination with a dental engine of an attachment, comprising a bellows, a slide-way formed on the pedal of said engine, a carriage arranged to move freely in said slide-way, means for locking said carriage in said slide-way and means for operatively connecting said carriage with said pump so that actuating the pedal of the dental engine will operate the pump.

40 2. The combination with a dental engine of an attachment comprising a bellows, a block secured to the pedal of the dental engine, a slideway formed in said block, teeth arranged in said slideway, a carriage arranged to travel 45 in said slideway, a pawl mounted on said carriage and arranged to engage said teeth, means for lifting the pawl out of engagement with said teeth and a cord connecting said bellows and said carriage, substantially as described 50 and for the purpose set forth.

55 3. The combination with a dental engine of an attachment comprising a bellows, a block secured to the pedal of the dental engine, a

60 slideway formed in said block, holes formed in the bottom of the said slideway, teeth removably secured in said holes, a carriage arranged to travel in said slideway, a pawl mounted on said carriage and arranged to engage said teeth, means for lifting said pawl out of engagement with said teeth and a cord connecting said bellows and said carriage, substantially as described. 65

4. The combination with a dental engine of an attachment comprising, a bellows, a block secured to the pedal of said dental engine, a 70 slideway formed in said block, teeth arranged in said slideway, a carriage arranged to travel on said slideway, a pawl mounted on said carriage and arranged to engage said teeth, a stud mounted in said carriage and resting on 75 said pawl and a cord connecting said bellows and said carriage, substantially as described and for the purpose set forth.

5. The combination with a dental engine of an attachment, comprising, a bellows, a block 80 secured to the pedal of the dental engine, a slideway formed in said block, teeth removably secured in said slideway, a carriage arranged to travel in said slideway, a pawl mounted in said carriage and arranged to engage said teeth, means for lifting the pawl out of engagement with said teeth, a pin arranged transversely of said slideway, and a cord passing under said pin, and connecting the said bellows and the said carriage, 85 substantially as described and for the purpose set forth. 90

6. In a dental engine, the combination with the standard, treadle, and handpiece, of an attachment comprising a bellows supported on 95 said standard, a liquid-receptacle secured to the standard above said bellows, rigid tubes adjustably seated in stopper of said receptacle and adapted to extend into the same whereby said receptacle can be converted into a siphon, atomizer, or air-reservoir, a nozzle secured to the handpiece, a flexible tube connecting one of said rigid tubes with said nozzle, a flexible tube connecting the other of said rigid tubes with the bellows, and means for operatively connecting the bellows with the treadle, 100 substantially as described and for the purpose set forth. 105

In testimony whereof I sign the foregoing specification, in the presence of two witnesses, this 22d day of June, 1903, at Cleveland, Ohio.

ISIDOR LYMAN.
